UNITED STATES PATENT OFFICE.

MAX GARBELL, OF CHICAGO, ILLINOIS, ASSIGNOR TO GARBELL TYPEWRITER CORPORATION, OF CHICAGO, ILLINOIS, A CORPORATION OF DELAWARE.

TYPEWRITING MACHINE.

Application filed November 1, 1920. Serial No. 420,892.

To all whom it may concern:

Be it known that I, MAX GARBELL, a citizen of the United States, residing at Chicago, in the county of Cook and State 5 of Illinois, have invented a certain new and useful Improvement in Typewriting Machines, of which the following is a full, clear, concise, and exact description, reference being had to the accompanying drawings, forming a part of this specification.

This invention relates to improvements in typewriting machines, and more particularly to that class of typewriting machines wherein end-wise sliding type bars are employed arranged in a segmental group and radially movable to the common printing point.

As is well understood by those skilled in the art, in typewriting machines of the character mentioned in the preceding paragraph, it is necessary to provide centering guiding means or, as sometimes termed, deflecting means, for the type-carrying ends of the type bars as they approach the printing position. The various type bars, which are all arranged at different angles with respect to the usual platen, must be guided or deflected as they approach the printing position in order that the type faces may be 20 presented to the platen perpendicular thereto. Heretofore, so far as I am aware, it has been the universal custom in this class of typewriting machines to provide means on the type bars cooperable with the centering 25 guiding means or deflecting means which means on the type bars have been different for each type bar due to the different angles from which the type bars approach the platen. This prior practice has involved 30 relatively heavy expense because of the delicate and different machining operations required in connection with each of the type bars.

One object of my invention is to provide 35 an exceedingly simple arrangement for deflecting or centering the reciprocating or endwise movable type bars which arrangement may be employed without change on each of the type bars regardless of the position of the type bar in the group.

Another object of the invention is to provide 40 an arrangement of the character indicated in the preceding paragraph by which the construction is both materially simplified and the cost of manufacture greatly

reduced and at the same time a more accurate centering of the type obtained combined with a smoother action of the type bars with lessened friction.

A specific object of the invention is to provide 60 a novel type block or type head especially adapted for carrying out the preceding objects of the invention.

In the drawing forming a part of this specification, Figure 1 is a top plan view, 65 parts being broken away, of a typewriter showing my improvements in connection therewith, only such parts of the machine being illustrated as necessary to explain the invention. Figure 2 is a plan view, upon 70 an enlarged scale, illustrating the type bar centering means and the positions of the type bars as the same assume the printing position. Figure 3 is an enlarged vertical sectional view corresponding substantially 75 to the line 3—3 of Figure 2 and showing one of the type bars in printing position. Figure 4 is a detail horizontal sectional view corresponding substantially to the line 4—4 80 of Figure 3. Figure 5 is a side elevation 85 of the improved type block or type bar. Figure 6 is a detail perspective of the type block.

In the drawing, 10 denotes a platen of usual cylindrical form, 11 the combined 85 bottom guide and supporting plate for the reciprocating or endwise movable type bars A—A. As customary in machines of this type, the type bars A are arranged in the form of a segment and each is movable in a substantially radial line to the printing point designated at 12 in Figure 1. The type bars A may be actuated by any suitable means as for instance by the type bar action disclosed in my prior Patent 1,305, 90 893 and the type bars may be guided by any suitable means.

To properly center the various type bars as the latter reach the printing position, 100 the machine is provided with a lower set of converging guiding flanges 13—13 which, at their adjacent ends, provide a slot 14 the direction of which is perpendicular to the surface of the platen, shown in Figure 2. Corresponding similarly 105 arranged upper guide flanges 15—15 are provided, the same having a slot 16 similar to and aligned with the slot 14. The upper guide flanges 15 may be carried by a suitable bridge plate 17 sup- 110

ported by integral bracket arms 18, the latter being secured to any suitable portion of the main frame of the typewriter.

Each of the type bars A is preferably in 5 the form of a stamped skeleton-like plate 20 to the inner end of which is soldered the type block or head designated generally by the reference character B.

The type block or head B will preferably 10 be of steel and consists of a vertically elongated member slotted on its rear side as indicated at 21 so as to adapt it to fit over and be readily soldered to the plate 20. The type block B will be of greater vertical 15 height than the plate 20 and will be extended both below and above the plate 20 as indicated most clearly in Figure 3. On its front or active side, the block B is cut away so as to provide a depressed vertically extending 20 face 22 on which the printing characters 23—23 are formed as best shown in Figure 6. At its upper end the type block B is formed with an upwardly extended cylindrical projection or pin 24 of a diameter corresponding to the slot 16. At its lower end the type block B is provided with a similar 25 downwardly extending cylindrical projection or pin 25 corresponding in diameter to the slot 14. The axes of the cylindrical pins 24 and 25 coincide and the common axis corresponds to a line flush with the outer edges of the type characters 23 and centrally thereof, as will be best seen from an inspection of Figure 5. At its lower end, the type block 30 B is also provided with depending flanges 27—27 spaced rearwardly or inwardly of the pin 25, having the lower edges thereof flush with the lower end of the pin 25 so that the type block will always obtain a support 35 at the bottom face though the pin 25 may have passed slightly beyond the supporting plate 11. With this construction it will be noted that it is impossible for the pin 25 to drop downwardly and catch and thereby 40 lock or jam the machine, and the flanges 27—27 will not engage the guide flanges 13—13.

In carrying out my invention, the type 45 blocks B will first be embossed with the desired type with the face 22 arranged at the proper angle corresponding to the position of the type bar to which the block is to be applied. The type block will next preferably be turned so as to produce the cylindrical ends or pins 24 and 25 which is obviously a simple operation and independent of the particular angle of the face 22 of the block. The type blocks will then preferably be slotted to define the groove 21 when they are 50 then ready to be applied to the type bars. With the construction described, it is evident that, regardless of the angle from which the type bar approaches the platen, as illustrated by the two extreme dotted type bars 55 in Figure 2, the pins 24 and 25 will always

pass into the guiding or centering slots 14 and 16 and positively insure the type striking the platen in a direction perpendicular thereto. Furthermore, the type will always 60 positively be centered with respect to the guiding slots 14 and 16 since the cylindrical pins are made of a diameter to correspond with the width of said slots, and wobbling or lateral play of the type block at the printing position is eliminated. Furthermore, by 65 employing the cylindrical guide pins 24 and 25, I minimize the friction and eliminate danger of "sticking" which has been a serious defect in typewriters of this general 70 class, heretofore.

From the preceding description, considered in connection with the drawing, it will be seen that the type blocks B may be manufactured in quantities inasmuch as the same are duplicates for all type bars in so far as 75 the formation of the centering pins is concerned, and the cost is thereby reduced to a 80 minimum.

I have herein shown and described what I now consider the preferred manner of carrying out the invention but the same is merely illustrative and I contemplate all 85 changes and modifications that come within the scope of the claims appended hereto.

I claim:

1. In a typewriting machine, the combination with a platen and an endwise movable type bar; of type bar centering guiding means adjacent the platen; and a type block 90 mounted on the type bar, said block having cylindrical pin-like projections cooperable with said means, the axes of said pin-like projections coinciding with a line flush with the edges of the printing characters on the type block.

2. In a typewriting machine, the combination with a platen; of type bar centering guiding means adjacent the platen at the printing position, said means including upper and lower sets of converging guiding 100 walls and slots perpendicular to the platen; and an endwise movable type bar having a type block at its inner end, said block being provided with upwardly and downwardly projecting cylindrical pins cooperable with said means, the diameters of the pins corresponding to the width of said slots and the pins being aligned with the type characters of the block.

3. In a typewriting machine, the combination with a platen, type bar centering guiding means adjacent the platen at the printing position, and a horizontal combined supporting and bottom guide plate; of an endwise movable type bar provided at its inner end with upper and lower pin-like extensions cooperable with said means, said type bar being provided also with a downwardly extended flange spaced inwardly of the lower 110 of said pin-like projections by which the 115

type bar is adapted to be supported in the event said lower pin-like extension passes beyond the plate.

4. As an article of manufacture, a type block for typewriters, said block being slotted lengthwise on one side thereof and provided with integral printing characters on the opposite side, said block being formed at the top and bottom thereof with upward-
10 ly and downwardly extending pin-like projections out of alinement with the slot.

5. As an article of manufacture, a type block, said block being formed with integral, alined, cylindrical pin-like projections at its ends, said projections being alined 10 with the printing characters of the block.

MAX GARBELL.
